UNITED STATES PATENT OFFICE.

JOHN C. McFARLAND, OF LA GRANDE, OREGON.

MATRIX-MACHINE.

1,299,749.

Specification of Letters Patent. Patented Apr. 8, 1919.

Application filed December 31, 1917. Serial No. 209,695.

To all whom it may concern:

Be it known that I, JOHN C. McFARLAND, a citizen of the United States, residing at La Grande, in the county of Union and State 5 of Oregon, have invented certain new and useful Improvements in Matrix-Machines, of which the following is a specification:

This invention relates to machines for making matrices for use in the formation 10 of stereotype or similar plates to be employed upon printing presses. The primary object of my invention is to provide a machine which may be operated in the ordinary manner of a typewriter to produce a 15 mold from or in which a stereotype plate may be cast. Another object of the invention is to provide a simple machine by the use of which a matrix may be very rapidly and cheaply produced and which may be 20 automatically fed forward as a line of characters is formed.

The invention is illustrated in the accompanying drawings and consists in certain 25 novel features which will be first fully described and then more particularly pointed out in the appended claims, and in the drawings:

Figure 1 is a front elevation of a machine embodying my improvements, some of 30 the parts being omitted in order to avoid confusion in the illustration;

Fig. 2 is a side elevation of the improved machine;

Fig. 3 is a perspective view of the frame 35 of the machine;

Fig. 4 is a detail perspective view of a mold carrier;

In carrying out my invention, I employ a frame 1 which may be of the same general 40 form as the frames of typewriters now in use and in which the type bars are disposed in rear of the carrier and are operated by keys at the front of the machine to move downwardly and forwardly to make an impression. The frame comprises front standards 2 which are disposed on the side bars of the base portion of the frame and are rigidly connected by transverse stay-bolts or rods 3. The frame also comprises 45 the standards 4 which are disposed in rear of the standards 2 and are connected at their upper ends and at intermediate points of their height by the rearwardly extending arcuate braces 5, the upper of said braces 50 constituting a rest for the upper ends of the type bars 6 and the lower of said braces 55

constituting a bracket or support for the bearings 7 in which the said type bars are pivoted. The arcuate form of these braces and the consequent curve or arcuate arrangement of the type bars mounted thereon will cause the type faces 8, which are provided at the free ends of the bars, to strike at a common point upon the mold which point obviously is the center about which the arcs defined by the braces are described. The type bars are provided near their lower pivoted ends on their front edges with perforated lugs or ears 9 and links 10 are pivoted at their upper ends to said lugs, the 70 lower ends of the said links being pivoted to the key levers 12 which are pivoted at their rear ends in suitable bearings on the frame and at their front ends carry keys 13 arranged across the front of the machine. 75

The stay-bolts or rods 3 constitute tracks for a carrier provided at its ends with collars or bearings 14 which are slidably mounted upon the said stay-bolts or rods, the said rods and the bearings being preferably circular in cross-section so as to facilitate the assembling of the parts and also reduce frictional wear. The carrier 15 is preferably in the form of a plate bridging the space between the track members 3 and 80 provided at its ends with the depending flanges or end walls 16 through which extends a shaft 17 on the ends of which are secured spur gears 18. One end of the shaft 17 may be somewhat extended so as to carry 85 a ratchet wheel 19 and a milled disk or head 20, the said milled disk or head being intended for manipulation so that any desired character in the mold may be closely examined and corrected when necessary. The 90 ratchet wheel 19 is intended to be engaged by a dog 21 secured upon the front side of the carrier 15 so that the mold may be held at any position to which it is moved. A line-feed bar 40 is mounted in off sets 41 provided on the carrier and carries a dog 42 working through a guide 43 to engage the ratchet wheel 19. Movement of the bar 40 will carry the dog 42 against the ratchet wheel so that the latter will be partly rotated in the well-known manner. At the 95 rear side of the carrier 15 is a depending rack 22 which is engaged by a pinion 23 controlled by an escapement device 24 which may be of the same construction as the well-known escapement device now employed on all typewriters and operated by an escape-

ment bar 25 passing transversely beneath all the key levers 12 in the well-known manner. These elements for controlling the line spacing may be constructed in their specific details in the same manner as similar elements of ordinary typewriters and are illustrated in the accompanying drawings in a more or less conventional manner.

On the upper side of the carrier 15 at the 10 ends thereof are bosses or other forms of enlargements indicated at 26 and upon the upper sides of these bosses or enlargements are secured in any convenient manner track members 27, which are shown in the present 15 drawings as of circular cross-section. The mold car is guided by these tracks and it consists of a plate 28 of suitable size and form provided on its under side at its ends with racks 29 adapted to mesh with the spur gears 20 18, as shown most clearly in Fig. 1, whereby as the said gears are rotated the mold will be moved rearward so as to bring the mold into position to properly space a succeeding line from the line which has been formed. 25 Upon the under side of the mold car 28, I provide a plurality of depending stub shafts 30 and upon each of said shafts is mounted a grooved guide roller or pulley 31 which is adapted to bear against the inner portion of 30 the respectively adjacent rail or track member 27 and thereby guide the mold car in its movement. The circular form of the members 27 with the correspondingly shaped peripheral grooves of the guide rollers aids in 35 supporting the mold car so that the weight of the same and the mold placed thereon will not be entirely borne by the spur gears 18 and the strain upon the said gears to move the mold and its car will be thereby minimized. 40 The rollers 31 and the track members 27 obviously will prevent movement of the car longitudinally of the carrier 15 so that the movement of the mold across the machine will only be such as is permitted by 45 the escapement device 24 which controls the transverse movement of the carrier 15. The mold may be of any suitable material ordinarily employed for the casting of type faces from type metal and the upper surface of 50 the mold and the mold car may be curved, as illustrated, or may be plane. The tracks 27 will, of course, be straight or curved accordingly as the mold has a curved or plane upper surface and whether a curved or plane 55 surface is used depends solely on the form of press to which the stereotype plate is to be applied.

A spring drum 32 and connecting tape 33 of the usual form are provided to move the 60 carrier after each type face has been caused to make an impression in the mold and the extent of such movement is regulated by the escapement device.

It is, of course, desirable that the type 65 faces all impress in the mold to the same

depth so that the characters formed from the matrix will have their printing faces in the same plane to exert the same printing force upon the paper. To this end, each type bar 6 has its end 45 projected beyond the type 70 face 8 and a suitable stop is provided above the mold to extend into the path of this projected end 45 so as to limit the downward movement of the bar. A cross bar or other support 46 is secured rigidly upon the main 75 frame 2 and at the center of this cross bar, I mount therein a pin or stud 47 which is provided at its lower end with the rearwardly projecting lug or spur 48. The upper extremity of the pin or stud 47 is threaded and 80 carries a wing nut 49 which is turned against the cross bar 46 so as to support the pin at the proper point vertically to permit the type faces to make the desired impression upon the mold. A spring 50 is coiled around the pin or stud 47 between the lug 48 and the cross bar 46 so as to yieldably hold the lug in the lowest position permitted by the adjustment of the nut 49. When the type bar is swung downwardly and forwardly to 90 make an impression in the mold, the extended end thereof will impinge against the lug 48 and its downward movement will thereby be arrested, the result being that all the type faces will penetrate the material of 95 the mold to the same depth. The spring 50, however, will permit the lug, and the pin 47 on which the lug is formed, to be raised when necessary to avoid injury to any of the parts when the mold is being inserted in or removed from the machine.

It will be readily noted from the foregoing description, taken in connection with the accompanying drawings, that I have provided a very simple mechanism whereby 105 matrices may be very rapidly and economically produced. The machine will be operated in exactly the same manner as the ordinary typewriter so that high speed in the production of the matrix will be attained by 110 skilled operators and ordinary type setting will be entirely eliminated. The type bars may be provided in any desired number and will preferably be provided in interchangeable series so that a machine may be arranged to produce type faces of any desired form. The molds and the mold cars will be of such dimensions that they may be readily placed in position upon the machine and will not impose an excessive strain thereon 115 so that the movement of the parts will be free and easy at all times. If desired, the machine may be furnished with a large number of mold cars so that molds may be placed upon several cars and after a car carrying 120 a mold has been fed rearward to the limit of its movement, a second car with a mold thereon may be at once placed in position without loss of time. To insert a car with an attached mold in place, it is necessary 125 130

merely to position the car so that the rollers 31 carried thereby will be between the track members or rails 27 and the car is then brought forward so that the said rollers will engage the said rails and the racks 29 will mesh with the spur gears 18. The machine is then operated so as to cause the desired type faces to successively strike into the material of the mold and make an impression 10 or matrix therein. When the last line has been formed the car and the mold may be simply moved rearward past the ends of the track members 27 and thereby disengaged therefrom so that the mold may be placed 15 in any convenient support and type metal poured thereon in the usual manner to produce the stereotype plate.

Having thus described the invention, what is claimed as new is:

20 1. In an apparatus for the purpose set forth, the combination of a supporting frame, spaced transverse guides secured thereon, a carrier slidably mounted on said guides, central projections on the upper side 25 of the carrier at the ends thereof, track members fixed to said projections and extending forwardly and rearwardly therefrom beyond the carrier, said track members being free through their entire extent 30 in front of and in rear of the projections, a mold car engageable with said track members over the ends of the same, means for moving the carrier along the transverse guides, and means for moving the mold car 35 along the track members.

2. In an apparatus for the purpose set forth, the combination of a supporting frame, spaced transverse guides secured in 40 said frame, a carrier slidably mounted on said guides, track members on the upper

side of said carrier, a mold car engaging said track members and provided at its ends on its under side with racks disposed at the outer sides of said track members, a shaft mounted in the carrier, spur gears on said shaft 45 engaging said racks, and means for intermittently rotating said shaft.

3. In an apparatus for the purpose set forth, the combination of a supporting frame, spaced transverse guides in said frame, a carrier slidably mounted on said guides and provided at its rear side with a depending rack, an escapement device co-operating with said rack, means acting constantly to move the carrier in one direction, 50 track members on the upper side of the carrier and extending longitudinally of the supporting frame, a mold car disposed above said track members and extending over the same, guide pulleys on the under side of the 55 mold car engaging said track members, and means on the carrier and the mold car for moving the mold car along said track members.

4. An apparatus for the purpose set forth 60 comprising a mold, a plurality of type-forming members mounted in rear of the mold, means for swinging the type-forming members downwardly and forwardly to the mold, a support, a pin mounted therein and 65 provided at its lower end with a stop extending into the path of the type-forming members, means on the upper end of said pin to retain it in the fixed support, and yieldable means between the support and 70 the lower end of the pin to hold the pin normally lowered.

In testimony whereof I affix my signature.

JOHN C. McFARLAND. [L.S.]
